J. A. McCARTHY

ROOFING SHINGLE

Filed Jan. 20, 1926

INVENTOR
John A. McCarthy.
BY
Anthony J. Brown
ATTORNEY

UNITED STATES PATENT OFFICE.

JOHN AUGUSTUS McCARTHY, OF ST. JOSEPH, MISSOURI.

ROOFING SHINGLE.

Application filed January 20, 1926. Serial No. 82,458.

My invention relates to roofing shingles and more particularly to what is commonly known as a composition or asphalt shingle of the interlocking type, the principal object of 5 the invention being to provide a shingle of this composition and type which may interlock with other like shingles in an adjacent course to align the shingles of a roof in horizontal courses and to break joints in successive courses to form a roof of substantially 10 continuous sheet construction having the appearance of an ordinary shingled roof.

Another object of the invention is to provide a shingle wherein the interlocking elements are so arranged that when a proper 15 number of the shingles are assembled in a roof their exposed or weather portions are of uniform size, thereby maintaining an even pattern.

20 In accomplishing these and other objects of the invention I have provided improved details of structure, the preferred forms of which are illustrated in the accompanying drawings, wherein

25 Fig. 1 is a perspective view of a section of roof covered with shingles embodying my invention, parts being broken away and some of the shingles being shown in assembling position for better illustration.

30 Fig. 2 is a detail, fragmentary, perspective view of portions of adjacent shingles of one roof course, illustrating the locking tongue or key of a subsequent course about to be interlocked in the key slot formed between the 35 adjacent shingles of the first course.

Fig. 3 is a similar view with the tongue inserted to form the interlock.

Fig. 4 illustrates the construction assembly of a further modified form of shingle 40 embodying my invention.

Referring more in detail to the drawings by numerals of reference:—

1 designates a shingle cut from a sheet of composition, asphalt or like roofing material, 45 comprising a body portion 2 of substantially rectangular shape provided centrally of one end with an integral extension 3, having laterally extending ears 4 and 5 cut at an angle to form the notches 6 and 7 and provide a key member 8 for interlocking the shingle with other like shingles when a number of the shingles are assembled to form a roof covering.

In the edges of each shingle, about its 55 longitudinal center are notches 9 and 10, the portion of the shingle at the lower or weather

end 11 of the shingles being narrower than the cover portion 12, to provide spear shaped slots 13 between adjacent shingles in a course when the shingles are assembled on a roof. 60

The shingles are preferably cut in transverse rows from a sheet or roll of roofing material and in order to prevent waste of material the keys on the ends of one row of shingles are cut from this portion of the roll 65 which will constitute the material for the second row of shingles when the first row of shingles is removed, so that each shingle has the key 8 at one end and the recess 14 at the other end, the edges 15 and 16 of the keys 70 being cut on converging lines, forming V shaped seats 17 at the bottoms of the recesses which may serve as guides in laying the shingles.

In laying the shingles a strip of felt roofing 75 18 is laid along the edge of the roof upon the sheathing 19 and nailed or cemented in place, after which a second strip 20, having spear shaped slots 21 provided at their upper ends with notches 21', similar to the notches 80 9 and 10, spaced at intervals along its lower edge to receive the keys 8 on the first row of shingles.

In applying each shingle of the first course one of the ears 4 or 5 of its key 8 is 85 inserted in the head of a slot 21 and under the strip 20, the other ear being slipped into a notch 21', so that by rotating the shingle to bring it to a right angle with the edge of the roof, its other ear is moved to position 90 under the strip.

After the first course of shingles has been set, a second course is applied with the keys inserted into the spear shaped recesses constituting housings formed by adjacent 95 shingles in a manner similar to the application of the shingles of the first course to the strip 20, the upper ends of the shingles of each course being nailed as at 22 and 23 in the same manner as ordinary non-lock shingles are nailed.

100 After the key of a shingle has been applied through a spear shaped slot and its ears engaged under the edges of the adjacent shingles as described, it cannot be removed 105 without rotating the shingle, reversely to movement required of its insertion, and since the shingle is firmly nailed in place, it is impossible for it to curl into such a position that it can get out of the slot, thus 110 locking the center of the shingle and holding it down tightly over the joint at the upper

ends of the shingles in the next lower course, the point at which a roof is most apt to leak, because of separation of the shingles by warping or wind pressure.

5 Attention is called to the fact that the base of the head of the spear-shaped slot is equal to the width of the key at its throat, and may be varied according to the width of key desired, and that the spacing of the 10 vertical sides of the slot is maintained by the abutting edges of the enlarged upper portions of the shingles, so that all spaces will be maintained uniform.

As before mentioned, the recess at the top 15 of each shingle serves as a guide for vertically aligning the shingles, since the edges of the shingles in the course under construction may be aligned with the vertex of the notch at the bottom of the recess, as indicated at 24 in Fig. 1.

In the construction shown in Fig. 4, the locking key is placed at the lower point of the diamond, as at 25, and the notches 26 and 27, which are equivalent to the notches 25 9 and 10 in the square type of shingle are cut in the horizontal corners of the diamond to provide substantially the same interlock as in the preferred construction, but pro-

viding a roofing of only a single thickness.

From the foregoing it will be apparent 30 that shingles constructed according to my invention cannot curl nor blow loose, and being locked one to the other in regular courses, will provide a roof of pleasing appearance and great serviceability. 35

What I claim and desire to secure by Letters Patent is:—

1. A shingle having a locking key near the center of its butt having laterally extending portions, and a semi-spear shaped housing 40 in a vertical edge, the narrowest diameter of the key being substantially equal to the radius of the curve of the semi-spear shaped recess. 45

2. A shingle having a locking key near the center of its butt having laterally extending portions, and a semi-spear shaped housing in a vertical edge, the narrowest diameter of the key being substantially equal to the radius of the curve of the semi-spear shaped recess and substantially equal to twice the base of the semi-spear shaped housing. 50

In testimony whereof I affix my signature.

JOHN AUGUSTUS McCARTHY.
